UNITED STATES PATENT OFFICE.

EDWARD E. HINRICHSEN, OF EAST ORANGE, NEW JERSEY, ASSIGNOR, BY MESNE
ASSIGNMENTS, TO WESTERN ELECTRIC COMPANY, INCORPORATED, A CORPORATION
OF NEW YORK.

TELEPHONE SYSTEM.

1,203,336.

Specification of Letters Patent. Patented Oct. 31, 1916.

Application filed October 6, 1915. Serial No. 54,336.

To all whom it may concern:

Be it known that I, EDWARD E. HINRICHSEN, a citizen of the United States, residing at East Orange, in the county of 5 Essex and State of New Jersey, have invented certain new and useful Improvements in Telephone Systems, of which the following is a full, clear, concise, and exact description.

10 This invention relates to telephone systems, and more particularly to such systems of the type wherein connections are to be established between subscribers' stations terminating in central offices widely separated.

15 An object of this invention is to provide a system of this character wherein an operator at a central office may select any one of a plurality of local offices radiating from 20 a second central office which may be more or less remote to the first without the intervention of an operator at the second central office.

25 Another object of this invention is to provide improved signaling means for a system of this character.

30 A further object of this invention is the provision of such a system in which a trunk circuit between the two central offices may be used as the selecting circuit for selecting the desired local office.

35 A still further object of this invention is the provision of such a system in which the trunk circuit between the two central offices may be used as an extension of a call wire circuit (between the second central office and an office local thereto), whereby the operator at the first central office may communicate direct with an operator at the selected local office.

40 In accordance with this invention, a main trunk circuit extends from one central office to a second central office, and local trunk circuits and associated call or order wire circuits extend from the second central office to a plurality of offices local thereto. Apparatus located at the second central office controlled over the main trunk circuit by selecting keys at the first central office selects 45 the desired local trunk and connects the associated call wire circuit thereof to the main trunk circuit. After the proper instructions have been transmitted by the op-

erator at the first central office to the operator at the selected local office, the release 55 of the selecting key permits the connection of the main trunk between the first and second central office with the local trunk between the second central office and the selected local office. Apparatus associated 60 with the main trunk and the local office trunks permits all supervising to be handled from the first or originating central office.

This invention will be more fully understood by reference to the accompanying 65 drawings illustrating one embodiment of the invention.

To obtain a clear idea of the entire system, the figures should be placed side by side in the following order from left to 70 right,—1, 2, 3, 4.

The system illustrated in the drawings 75 involves two central offices, one to be hereinafter referred to as the first or originating central office, and the other as the second central office. At the first central office there is located a toll cord circuit A, shown in Fig. 1. Between the first and second central offices there extends a main trunk circuit B, the outgoing end of which is 80 shown in Fig. 2 and the incoming end in Fig. 3. Local trunk circuits C and associated call wire or order wire circuits D extend from the second central office to local offices E, F and G. There is one local trunk 85 circuit and one call wire circuit into each local office. The outgoing ends of the local trunk and call wire circuits are shown at the right of Fig. 3, while the incoming end of one local trunk circuit and one call wire 90 circuit and equipment thereof for local office E are shown to the right in Fig. 4. The equipment for the incoming ends of the local trunk circuits and call wire circuits to F and G are not shown in the drawings. 95

Since the originating subscriber's line forms no part of this invention, it has not been shown in the drawings.

Assuming that the operator at the first 100 central office has received a call for a subscriber whose line terminates in local office E, local to the second central office, the operator will insert calling plug 6 into jack 7 of the main trunk circuit B, thereby energizing 105 relay 8 over a circuit from battery

BEST AVAILABLE COP

through relay 9, sleeve contacts of the plug and jack, windings of relay 8 and contact 10 of relay 11 to ground. Relay 8 in operating, causes the actuation of relay 12 which connects the talking strands of the main trunk circuit B through to the tip and ring contacts of the jack 7, and opens the circuit of relay 11 at the normal contact of relay 8, thereby preventing the connection of a second cord circuit to the main trunk circuit B during the connection therewith of cord circuit A. The actuation of relay 12 also causes the operation of relay 13 over a circuit which may be traced from battery 18 through the winding of relay 13, contact 14 of relay 12, and contact 15 of relay 16 to ground. The operation of relay 13 connects negative signaling battery through the normal contact of relay 21, normal contact of relay 23, winding of relay 24, contact 25 of relay 13, one winding of retardation coil 26, ring side of the main trunk circuit B, one winding of retardation coil 27, windings of relays 28 and 29, and the upper winding of relay 30 to ground through the contact of relay 32. Relay 24 operates, short-circuiting one winding of relay 8, thereupon permitting sufficient current to flow through the winding of relay 9 to cause the actuation of this relay, whereupon lamp 33 in the calling end of the cord circuit A is lighted. Relays 28 and 30 are operated by the flow of negative signaling battery, relay 28 causing the operation of relay 34, which closes its contact 35 placing ground on the armature of relay 30. However, the relay 34 is slow in operating, so that relay 30 has time to fully operate, opening its contact 36 before relay 34 closes its contact 35, thereby preventing the operation of relay 37 when the calling plug of the cord is first plugged into the jack of the main trunk circuit. Relay 29 is a polarized relay and does not operate on negative signaling battery. The operator may now actuate listening key 40 to connect the operator's telephone set with the cord circuit and actuate the proper selecting key for selecting the desired local office.

45 41, 42 and 43 indicate the selecting keys, the key 41 for selecting local office E, the key 42 for selecting local office F and the key 43 for selecting local office G. The actuation of key 41 grounds the ring side, key 42 grounds both sides and key 43 grounds the tip side of the line. Assuming that the desired subscriber's line terminates in local office E, the operator will depress key 41 which causes the operation of relay 50 21 over a circuit from battery through the winding of relay 21, ring side of the main trunk circuit, ring contacts of the jack and plug, and ring side of the cord circuit, to ground through the contact of key 41. The operation of relay 21 opens its normal contact and closes its alternate contact, thereby shifting from negative to positive signaling battery. Relay 29 thereupon operates, causing the operation of relay 51 which in turn completes a path for current through the winding of relay 52, which operates over a circuit from battery through the contact of relay 52, winding of relay 55, lower winding of relay 56, contact 58 of relay 57 and contact 59 of relay 51 to ground. Relays 52 and 51 having operated, 55 relays 55 and 56 now operate over a circuit from battery through the contact of relay 52, winding of relay 55, lower winding of relay 56, contact 58 of relay 57 and contact 59 of relay 51 to ground. The operation of relay 56 closes a locking circuit for itself at contact 60, this circuit being from battery through the winding of relay 32, winding of relay 61, upper winding of relay 56, contact 60 thereof, contact 62 of relay 63, contact 64 of relay 65, and the contact of relay 67 to ground, relay 67 having been operated by the operation of relay 52. Relay 52 is slow in operating so that relay 51 will have time to operate completely before relay 56 can operate. The operation of relay 55 closes its contacts 65, 66 and 167, and the operation of relay 61 closes its contacts, extending the main trunk circuit through to the armatures of relay 70. Relay 56 also closes its contact 74, causing the operation of relays 75 and 76. Relay 32, the circuit of which was closed by the operation of relay 56, is slow in operating, so that relay 75 has time to close its contact before relay 32 opens its contact, thereby maintaining the short circuit of the lower winding of relay 30 and resistance 31.

55 The operation of relay 76 lights lamp 77 before the operator at local office E. If the call wire circuit extending to local office E is not busy, the closure of contact 66 causes the operation of relay 70 over a circuit from battery through the contact and left-hand winding of relay 71, contact 68 of relay 55, winding of relay 70 and winding of relay 72 to ground. Relay 71 is marginal and does not operate when included in series with relays 70 and 72, but does operate when included in circuit with relay 70 only. Relay 70 in operating, completes the connection of the main trunk circuit B to the call wire circuit extending from the second central office to local office E. Relay 70 in operating also closes its contact 73 which short-circuits relay 72, preventing the operation thereof, causing the operation of relay 71. The operator at the first central office may now communicate to the operator at local office E the number of the line to which connection is desired. The operator at local office E now inserts the plug of the local trunk circuit C into the jack of the desired subscriber's line, whereupon relay 78 is operated, extinguishing lamp 77. The cutoff 60 123 125 130

relay of the subscriber's line is also operated. The operator at the first central office may now release selecting key 41, thereby releasing relay 21, which reverses the polarity of battery current through relay 29, which thereupon releases. Relays 51, 52 and 67 now release. Relay 67 is slow in releasing so that relay 51 may release first and establish an alternate locking circuit for relays 56 and 61, this circuit being from battery through the windings of relays 32 and 61, contact 60 and upper winding of relay 56, contact 62 of relay 63, contact 64 of relay 65, contact 79 of relay 51, contact 54 of relay 37 and contact 35 of relay 34 to ground. The release of relays 51 and 52 releases relay 55, which disconnects the main trunk circuit B from the call wire circuit D and connects trunk circuit B with the local trunk circuit C. Relay 55, in releasing, releases relays 70 and 71, which restores the call wire circuit D to its normal condition.

The operator at the first central office now restores listening key 40 to its original position and actuates ringing key 80 to connect a source of ringing current 81 to the ring side and ground to the tip side of the calling end of the cord circuit A, whereupon relay 82 is actuated, causing the operation of relays 83 and 84. Relay 83, in operating, connects the tip and ring conductors of the main trunk circuit B to the secondary of a transformer 85, the primary of which has been included in closed circuit with a source of alternating current 86 and interrupter 99 by the operation of relay 84. High frequency current from the secondary of transformer 85 passes through repeating coil 87 and operates relay 88. Relay 89 is normally energized, so, when relay 88 operates, relay 89 releases, causing the operation of relay 90. Relay 89 is slow in releasing so that it will not release and cause false rings should relay 88 be energized momentarily due to disturbances on the trunk. Relay 90, in operating, connects a source of ringing current 91 through the local trunk circuit C, causing the operation of relay 92, whereupon relay 93 is energized connecting a source of ringing current 94 at the local office E to the called line. Ringing current remains connected to the called line only as long as the operator at the first central office keeps ringing key 80 operated.

In response to the operation of the call bell at the station, the subscriber removes the receiver from the switchhook, causing the operation of supervisory relay 95 which removes the short circuit of resistance 96, whereupon relay 75 receives a reduced flow of current and releases. The release of relay 75 removes the short circuit of the lower winding of relay 30 and resistance 31, thereby reducing the amount of current through relay 24, causing the release thereof.

Relay 30 remains operated. Relay 24, in releasing, causes the release of relay 9, thereby extinguishing supervisory lamp 33.

At the termination of the conversation, relay 9 is again energized, relighting supervisory lamp 33, which serves as a disconnect signal to the operator at the first central office. The operator now withdraws the plug 6 from the jack 7, whereupon relays 8, 12, 13 and 24 of the outgoing end and relays 28, 34, 30, 32, 61 and 56 of the incoming end of the main trunk circuit B release. Relay 56 in releasing, releases relay 76, which causes the lighting of supervisory signal 77 to furnish a disconnect signal to the operator at the local office E, who thereupon withdraws the plug from the jack of the line restoring all apparatus to normal.

Should the desired subscriber's line have been one terminating in the local office F, the operator at the first central office would have selected the local trunk to this office by depressing selecting key 42. Relays 21 and 23 would thereupon operate, relay 21 shifting the polarity of signaling battery, and relay 23 removing the short circuit of resistance 50, releasing relays 24 and 30. The release of relay 24 extinguishes supervisory lamp 33. The changing of the polarity of the signaling battery operates relay 29 which causes the operation of relay 51, operating relays 52 and 67. The release of relay 30 operates relay 37, whereupon relays 63 and 69 operate, relay 63 completing a locking circuit through relays 32, 48 and 63. The local office F is now selected, and the main trunk circuit B is connected to the corresponding call wire circuit extending to the local office F. The remaining operations for completing the connection through to the subscriber in local office F is as hereinbefore described.

Should the desired subscriber's line have been one terminating in local office G, the operator at the first central office would have selected the local trunk to this office by depressing selecting key 43. Relay 23 would thereupon operate, removing the short circuit from resistance 50, releasing relays 24 and 30. The release of relay 24 extinguishes supervisory lamp 33, and the release of relay 30 causes the operation of relay 37, and in turn relays 52 and 67, whereupon relays 65 and 68 operate. Relay 65 in operating, completes a locking circuit through relays 32, 49 and 65. The local office G is now selected and the main trunk circuit B is connected to the corresponding call wire circuit extending to the local office G.

The call wire circuits D from the second central office to the local offices E, F and G are used in handling connections originating in the second central office and may be multiplied through the different operators' posi-

tions. 100 represents a call wire key at one such operator's position. Actuation of key 100, if the call wire circuit is not busy, causes the operation of relay 101, over a circuit from battery through the contact and left-hand winding of relay 71, lower contact of key 100, and the windings of relays 101 and 102 to ground. Relay 102 does not operate because relay 101 in operating closes its lower alternate contact 103, short-circuiting relay 102, causing the operation of relay 71. Operation of relay 101 also connects the operator's telephone set at the second central office to the call wire circuit extending to the local office E. Relay 71 in operating, removes the normal short circuit of the right-hand winding thereof, thereby including both windings in circuit. Should this call wire circuit have been busy when the operator at the second central office actuated key 100, both windings of relay 71 would have been in circuit, thereby preventing the operation of relay 101. Relay 102 would, however, have operated, lighting the lamp 104 and operating relay 105. The lighting of the lamp 104 indicates to the operator that the call wire circuit is in use, and the operation of relay 105 connects a tone to the receiver of the operator's telephone set which also indicates to the operator that the call wire circuit is in use.

Should the call wire circuit D extending to the local office have been in use when the operator at the first central office actuated listening key 40 and selecting key 41 to select the local office E, the prior operation of relay 71 would have prevented the operation of relay 70, but relay 72 would have operated. Relay 72 operating, would have connected a tone to the normal contacts 106 and 116 of relay 70, whereby a tone would have been transmitted to the receiver of the operator's telephone set at the first central office, indicating to this operator that the call wire circuit D extending to the local office E was in use.

Suppose that, while a connection is set up through the first and second central offices and the local office E, F or G to a subscriber's station of one of these local offices, the operator at the first central office should receive another call for connection to a subscriber's line terminating in one of the local offices which second connection would necessitate the use of the main trunk circuit B, the operator would insert the calling plug of a second cord circuit A into jack 107 of the main trunk circuit B. No apparatus associated with the main trunk circuit B is operated by the insertion of the calling plug, into the jack 107 while another calling plug is connected to the jack 7, for the energizing circuit of relay 11 is open at a contact of relay 8. As soon

receives the disconnect signal by the lighting of supervisory lamp 33 in the cord circuit A connected to jack 7, the calling plug 6 is withdrawn from jack 7. Relay 8 releases, causing the operation of relay 11, 70 which in turn operates relay 112, connecting tip and ring contacts of jack 107 with tip and ring conductors of the main trunk circuit B and closing the circuit of relay 16. The circuit of relay 16 is carried 75 through the normal contact of relay 13, so that relay 16 will not operate until after relay 13 has completely released, and the circuit of relay 13 is likewise carried through the normal contact of relay 16, so 80 that if relay 16 had previously been operated, relay 13 would not operate until after the complete release of relay 16. Relays 13 and 16 are slow in operating in order that relays 28 and 34 will have sufficient time 85 to release when a cord circuit is disconnected from one jack while another cord is connected to the other jack. The operation of relay 13 connects negative signaling battery to the ring side of the main trunk circuit 90 B, operating relays 28 and 30, as when relay 16 was operated upon the connection of cord circuit A with jack 7. The operator at the first central office may now actuate listening key 40 and the proper selecting 95 key to select the local office in which terminates the line of the desired subscriber.

The selecting keys and operator's telephone set shown in Fig. 1 are common to an operator's position. The apparatus included 100 within the dotted lines in Fig. 2 may be common to an operator's position or to the first central office.

After having communicated to the operator at the selected local office the number 105 of the desired subscriber's line, and after having released the selecting key, the operator at the first central office may find that the wrong number has been transmitted to the operator at the local office, that the 110 wrong local office has been selected, that the right local office has been selected but that the operator thereat has connected the local trunk circuit to the wrong subscriber's line, or the right subscriber's line may have been 115 connected with but the subscriber did not respond. In such cases, it is desirable that the first central office operator may be able to communicate with the operator at the desired local office without having to withdraw 120 the plug of the cord circuit from the jack of the main trunk circuit B. This is especially desirable for the reason that a second cord circuit may be connected with the second jack of the main trunk circuit. 125

The present invention provides for the contingencies above mentioned. Assuming, for example, that the proper local office has been selected and that the operator thereat has connected the incoming end of the local 130

trunk circuit C to the wrong subscriber's line, and assuming further that the office selected is local office E, the operator at the first central office may actuate listening key 5 40 and selecting key 41, which operates relay 21, whereupon polarized relay 29 operates, causing in turn the operation of relay 51. The operation of relay 51 opens the locking circuit of relays 56 and 61, which 10 thereupon release. The operation of relay 51 also operates relays 52 and 67, but relay 52 is slow in operating so that it does not close its contact until after relays 56 and 61 have fully operated. Upon the full 15 operation of relay 52, relays 55 and 56 operate, in the manner hereinbefore described, completing a locking circuit for relay 56 through relays 32 and 61. Relays 55 and 61 being operated, the main trunk circuit 20 B is connected to the call wire circuit D extending to the local office E, whereupon the operator at the first central office may give the proper instructions to the operator at the local office E.

25 What is claimed is:

1. A telephone system comprising a trunk circuit extending from a first to a second central office, call wire circuits, one extending from the second central office to each of 30 a plurality of local offices, a plurality of selecting keys at the first central office, means at the second central office selectively responsive to the actuation of one of said keys to connect said trunk circuit with one of said 35 call wire circuits, and a relay operating upon the selection of a local trunk circuit and locked up upon the release of the actuated selecting key to connect the main trunk circuit with the selected local trunk circuit.
- 40 2. In a telephone system, a main trunk circuit extending from a first to a second central office, local trunk circuits and associated call wire circuits, one of each extending from the second central office to each of 45 a plurality of local offices, a plurality of selecting keys at the first central office, means at the second central office selectively responsive to the actuation of any one of said keys to select one of said local trunk 50 circuits, and apparatus coöperating with said means to connect the corresponding call wire circuit with said main trunk circuit.
- 55 3. In a telephone system, a main trunk circuit extending from a first to a second central office, local trunk circuits and associated call wire circuits, one of each extending from the second central office to each of a plurality of local offices; a plurality of selecting keys at the first central office, means 60 at the second central office selectively responsive to the actuation of any one of said keys to select one of said local trunk circuits, and apparatus coöperating with said means to connect the corresponding call 65 wire circuit with said main trunk circuit,

said apparatus, upon the release of the actuated selecting key, serving to disconnect said call wire circuit from and to connect said selected local trunk circuit with said main trunk circuit. 70

4. In a telephone system, a main trunk circuit extending from a first to a second central office, local trunk circuits and associated call wire circuits, one of each extending from the second central office to each of 75 a plurality of local offices, a plurality of selecting keys at the first central office, a plurality of relays at the second central office selectively responsive to the actuation of one of said selecting keys and coöperating 80 to select one of said local trunk circuits, and relays operating upon the selection of a local trunk circuit to connect the corresponding call wire circuit with said main trunk circuit. 85

5. In a telephone system, a normally open main trunk circuit extending from a first to a second central office, a link circuit at the first central office, local trunk circuits and associated call wire circuits, one of each extending from the second central office to each of a plurality of local offices, a plurality of selecting keys associated with said link circuit, apparatus operating upon connection of said link with said main trunk-circuit to 90 close said normally open main trunk circuit, means at the second central office selectively responsive to the actuation of any one of said keys to select one of said local trunk circuits, and apparatus coöperating with 95 said means to connect the corresponding call wire circuit with said main trunk circuit. 100

6. In a telephone system, a main trunk circuit extending from a first to a second position, local trunk circuits and associated call wire circuits, one of each extending from the second position to each of a plurality of other positions, electromagnetically-controlled mechanism at the second position selectively responsive to currents of 105 different character for selecting one of the local trunk circuits and its associated call wire circuit, means at the first position for determining the character of current for selecting the mechanism, and a relay operating upon the selection of the local trunk circuit and its associated call wire circuit 110 for connecting the main trunk with the selected call wire circuit. 115

7. In a telephone system, a main trunk circuit extending from a first to a second central office, local trunk circuits and associated call wire circuits, one of each extending from the second central office to each of a plurality of local offices, a plurality of 120 selecting keys at the first central office, a neutral, a polarized and a marginal relay at the second central office selectively responsive to the actuation of one of said selecting keys and coöperating to select one of said 125 130

local trunk circuits, and relays operating upon the selection of the local trunk circuit to connect the corresponding call wire circuit with said main trunk circuit.

- 5 8. In a telephone system, a main trunk circuit extending from a first to a second central office, local trunk circuits and associated call wire circuits, one of each extending from the second central office to each of a plurality of local offices, a plurality of selecting keys at the first central office, a neutral, a polarized and a marginal relay at the second central office selectively responsive to the actuation of one of said selecting keys and coöperating to select one of said local trunk circuits and its associated call wire circuit, two relays operating upon the selection of the local trunk circuit to connect the selected call wire circuit with the main trunk circuit, the release of the actuated selecting key causing one of said last-mentioned relays to release to disconnect the call wire circuit from and to connect the corresponding local trunk circuit with the main trunk circuit, and a locking circuit for the other of the last-mentioned relays established upon the release of the actuated selecting key.
9. In a telephone system, a main trunk circuit extending from a first to a second central office, local trunk circuits and associated call wire circuits, one of each extending from the second central office to each of a plurality of local offices, a plurality of selecting keys at the first central office, a plurality of relays at the second central office selectively responsive to currents of different strength and polarity upon the actuation of one of said selecting keys and coöperating to select one of said local trunk circuits and its associated call wire circuit, and two relays operating upon the selection of the local trunk and associated call wire to connect the main trunk with the selected call wire circuit.
10. A telephone system comprising a main trunk circuit extending from a first to a second central office, local trunk circuits, one

extending from the second central office to each of a plurality of local offices, apparatus connecting the main with one of the local trunk circuits, a plurality of selecting keys at the first central office, and means at the second central office selectively responsive to the actuation of one of the keys to cause the disconnection of the main and local trunk circuits and to select the local trunk circuit corresponding to the actuated selecting key.

11. A telephone system comprising a main trunk circuit extending from a first to a second central office, local trunk circuits, one extending from the second central office to each of a plurality of local offices, a relay connecting the main with one of the local trunk circuits, a plurality of selecting keys at the first central office, and a plurality of relays at the second central office selectively responsive to the actuation of one of the keys to cause the release of the first-mentioned relay and to select the local trunk circuit corresponding to the actuated selecting key.

12. A telephone system comprising a main trunk circuit extending from a first to a second central office, a link circuit connected with the main trunk at the first central office, local trunk circuits and associated call wire circuits, one of each extending from the second central office to each of a plurality of local offices, apparatus at the second central office connecting the main trunk circuit with one of the local trunk circuits, a plurality of selecting keys at the first central office, means at the second central office selectively responsive to the actuation of one of the keys to disconnect the main trunk and the connected local trunk and to select the local trunk circuit corresponding to the actuated selecting key, and apparatus coöperating with said means to connect the call wire circuit corresponding to the selected trunk circuit with the main trunk circuit.

In witness whereof, I hereunto subscribe my name this 5th day of October A. D. 1915. 95

EDWARD E. HINRICHSEN.
